TYPEWRITER

Joseph Lee Sweeney and Harry Bates, New York,
N. Y., assignors to Bates Laboratories, Inc., New
York, N. Y.

Application May 13, 1938, Serial No. 207,819

19 Claims. (CL. 197—45)

This invention relates to improvements in typewriters and more particularly to a typewriter of such character that speed and volume of work are of secondary importance, but with which cost and educational value are of prime importance.

One of the objects of the invention is to provide a typewriter which may be manufactured at relatively small cost due to the fact that many moving parts of conventional typewriters are eliminated.

In accordance with the invention all the functions of the usual key levers of conventional typewriters are reduced in number, as the entire keyboard is on a single plate or dummy keyboard on which the usual key buttons are fastened in their normal correct positions, so that pressure on any key button will result in typing on the paper whatever type character happens to have previously been set. Accordingly, in order to have a specific character at a particular time, indicating and setting means are established on either side of the frame of the machine in the form of narrow cylinders around the peripheries of which are the various letters, numerals, punctuation marks, etc. These cylinders or small drums are operatively connected to a manually actuated rotatable shaft, the turning of which not only causes rotation of the cylinders but results in turning of a type wheel bearing characters corresponding to the type bars of conventional typewriters.

Instead of employing a plurality of character indicating cylinders, we may use a single cylinder, but this will necessitate crowding of the characters on the cylinder. We therefore prefer to use two cylinders instead of one, but appreciate that the same general result can be accomplished by employing a single cylinder.

Other objects of the invention will appear from the following description which should be read in connection with the accompanying drawings, in which

Fig. 1 is a top plan view, partly broken away, of a preferred form of our typewriter.

Fig. 2 is a bottom plan view of the same.

Fig. 3 is a longitudinal vertical sectional view of the machine.

Fig. 4 is a bottom plan view of the type wheel, the view being taken on the line 4—4 of Fig. 5.

Fig. 5 is a longitudinal vertical sectional view of a detail taken diametrically through the type wheel and partly in elevation.

Fig. 6 is an exploded perspective view of the pawl mechanism employed to temporarily lock the type wheel in position during printing.

Fig. 7 is a top plan view of the type wheel rotating member.

Fig. 8 is a side elevation of the same.

Fig. 9 is a sectional view partly in elevation taken on the line 9—9 of Fig. 3 and showing the escapement mechanism.

Fig. 10 is a side elevation of the main bearing for the rotating tube of the type wheel, shown detached from the machine.

Fig. 11 is a top plan view of the same.

Fig. 12 is a top plan view of a modification of the machine.

Fig. 13 is a longitudinal sectional view of the last-mentioned machine taken on the line 13—13 of Fig. 12.

Fig. 14 is a similar view of a detail taken on the line 14—14 of Fig. 12.

Fig. 15 is a top plan view, partly broken away, of a still further modification.

Fig. 16 is a longitudinal sectional view taken on the line 16—16 of Fig. 15.

Fig. 17 is a sectional view of a detail taken on the line 17—17 of Fig. 15.

Referring first to the embodiment of the invention illustrated in Figs. 1 to 11 inclusive, 20 (Fig. 2) designates an internal frame having a front wall 21, rear wall 22, side walls 23 and a top 24, the latter being stamped out at 25 to form a pair of spaced depending tongues 26, which (Figs. 3 and 4) form supports for a horizontal shaft or bearing pin 27 forming a rocking support for the levers 28. These levers diverge forwardly from the shaft 27 as indicated at 29 and their forward end portions 30 are rigidly secured to a depressible false keyboard 31.

As best shown in Fig. 1, the keyboard is provided with key buttons 32 all of which are fixed to the board and these buttons are arranged in exactly the same way as the keys of the keyboard of a standard typewriter.

At the rear end of the keyboard, a stationary index 33 is arranged, the latter being calibrated and having groups of characters 34, each group corresponding with the characters of the row of key buttons 32 with which the group is aligned. For example, the first row of key buttons bears the characters "l", "q", "a" and "z", and these will be the same characters as in the group 34 of the index which is aligned with the row.

This arrangement will aid in instructing a student as to the arrangement of the characters in each row, as a student will associate a particular group of characters with a particular row. Obviously such arrangement will facilitate

the teaching of typewriting in accordance with the touch system.

To further aid the student, a dividing bar or indicating line 35 may be positioned on the keyboard between the rows of buttons to be engaged by the right hand and the rows of buttons to be engaged by the left hand.

Reverting to the details of construction, the rear ends of the keyboard supporting levers, are preferably parallel as shown at 36 and they extend upwardly and rearwardly from the shaft 21 so as to engage the platen carriage 37 as indicated at 38.

The levers extend through slots 39 in the top of the frame of the machine.

The platen carriage is supported by a substantially inverted U-shaped member consisting of a substantially horizontal track or platform 40, from which legs 41 depend. These legs extend through slots 42 in the top of the frame and their lower ends are rockably supported by any suitable means such as horizontal bolts 43 that are secured to the side walls of the frame. Coil springs 44 surround the bolts, and each spring has one of its ends hooked under the lower edge of the rear wall of the frame, as indicated at 45, and its other end hooked through an apertured ear 46 formed on the corresponding leg 41. Such springs act to urge the platen rearwardly so as to cause the platen carriage to impinge against the rear ends of the levers 28 and yieldingly hold the dummy keyboard 31 in normal or elevated position (Fig. 3).

The platen carriage comprises a guide plate 47 having its side edges bent downwardly so as to slidably engage the side edges of the track or platform 40. One of the edges of the carriage plate (the front one) forms a toothed rack, the teeth of which are shown at 48 in Fig. 9. Such teeth form part of the escapement mechanism, which includes a rocking lever 49 that is pivotally connected at 50 by a vertical pin to the top 24 of the frame of the machine. The lever may be made of a piece of sheet metal, opposite side edges of which are turned upwardly to form an advancing pawl 50' and a locking pawl 51, each of which cooperates with the teeth of the rack. A downwardly extending lug 52 at the rear end of the lever, cooperates with the ends of a slot 53 in the top of the machine frame to limit the turning movement of the pawl.

The platform 40 of the rockable member is provided with a depending lug or finger 54, which projects forwardly and is adapted to engage the pawl 50' for moving the lever 49 in a counter-clockwise direction when the platen is moved forwardly. When such movement occurs, it is obvious that the teeth 48 are moved out of engagement with the pawls, and the lever 49 is moved into such position that when the rack on its return movement travels rearwardly, the pawl 50' will be in a position to engage a succeeding tooth of the rack, so as to advance the carriage one step for each cycle of the platen. When the parts move to the rearward position, the pawl 51 comes into a position between two of the teeth 48 and functions to lock the platen carriage against movement axially of the platen.

The platen is indicated at 55 and it is mounted on a hand-operated shaft 56 journaled in the end walls 57 of the carriage. 58 designates the paper guide and 59 the guide rollers of the platen carriage.

The platen is not only moved forward by the depression of the keyboard but is adapted to be 75

moved forwardly by the depression of a spacing bar 60. The latter is mounted on the forward ends of levers 61 which have their rear ends pivotally mounted on the shaft 21. Each of these levers is provided with a lug 62 (Fig. 3) which fits into a notch 63 in the complementary lever 28 of the keyboard. Consequently, each time the shift bar is depressed, the levers 61 will swing about the axis of the shaft 21, and the lugs 62 will bear downwardly against the forward end portions of the levers 28 to cause the rear end portions of the latter levers to act against the platen carriage and move the platen forward. Obviously, when the operator releases either the keyboard or the space bar 60, the springs 44 will function to return the parts to normal position.

Of course, when the spacing bar is depressed, the platen should not be moved into contact with the type wheel (hereinafter described), and therefore each lever 61 works in a vertical slot 61a in the front wall 21 of the machine frame, and the lower end of the slot forms an abutment edge 61b to limit the downward movement of the lever. Due to this construction, the platen can strike the type wheel when the keyboard is depressed, but cannot strike the type wheel when the spacing bar is depressed.

The platen cooperates with a type wheel 64 having upper and lower type character at the periphery thereof.

Such wheel is rigidly fixed to the upper end of a shaft 65. Pins 66 (Fig. 5) depend from the type wheel and loosely engage notches 67 (Fig. 7) in the ends of a bar 68. A tube 69 has its upper end fixed to the medial portion of the bar, and as best shown in Fig. 8, the tube is provided with a worm gear 70. The tube forms a bearing for the shaft 65 which extends through the tube so that the type wheel can be raised or lowered without disturbing the position of the tube.

The tube is journalled in a split bearing 71 (Figs. 5, 10 and 11) consisting of a front section 72 and a rear section 73; the front section having laterally extending trunnions 74 which fit into bayonet notches 75 in upstanding tongues 76 which are cut from the top 24 of the frame and are bent upwardly from the latter. This construction permits the split bearing to extend through the top of the frame at the point where the tongues are located, and the sections of the bearing are held in assembled relation by the front edge of a hinge plate 77 which in turn is held in place by a washer 78 secured to the top of the frame by a bolt 79.

The worm 70 of the tube which acts to turn the type wheel meshes with a worm or helical gear 80 fixed to a horizontal shaft 81 that is journalled in the side walls of the machine and provided at its ends with hand-operated knobs 82. Obviously when either one or both of the knobs are turned, the gearing 80, 70, will cause rotation of the bar 68 and the latter, through the instrumentation of the pins 66, will cause corresponding turning of the type wheel 64.

A pair of indicating cylinders 83 is fixedly mounted on the shaft 81, each cylinder being preferably arranged near one of the side walls of the machine. The cylinders between them bear characters 84 corresponding with the type characters on the wheel 64 and the characters on the key buttons 32 of the keyboard. In other words, each cylinder 83 will bear half of the characters. Consequently, the characters on each cylinder are arranged in staggered relation relatively to the characters on the other cylinder,

and these characters cooperate with stationary pointers 85 arranged at windows 86 in the case 89 of the machine.

The characters on the type wheel may be inked by any suitable means. For example, an inking ribbon 90 which passes about the periphery of the type wheel, may be guided by spools 91 which rotate on vertical shafts 92 extending upwardly from the top of the frame of the machine. As the ribbon is taut, turning of the type wheel will cause corresponding movement of the ribbon.

To permit use of both the upper and lower case characters of the inking wheel, the shaft 65 extends downwardly below the worm wheel 70 and through a table or bracket 93 fixed to the frame. A coil spring 94 surrounds the lower end portion of the shaft, and it is clamped between such table and a washer 95, the latter being adjustably held in position by nuts 96 attached to the threaded lower end 97 of the shaft.

The lower end of the shaft is arranged immediately above a trough-shaped abutment 98 formed integral with the rear ends of shift levers 99, the latter diverging forwardly and being pivotally mounted on a horizontal pin 100, which is journaled in tongues or ears 101 formed integral with the front wall 21 of the frame. The parts 98 and 99, as illustrated, may be made from a single piece of sheet metal, and the levers 99 terminate at their front ends in shift keys 102.

In order to lock the type wheel in position during printing, the underside of the wheel is provided with an internal annular ratchet 103 with which a pawl 104 cooperates; the pawl, as best shown in Figs. 5 and 6, may be formed on the upper end of a hinge element 105 having a hook 106 at its lower end to hingedly engage hooks 107 at the rear end of the hinge plate 77.

The member 105 is provided with notched ears 108, which engage the cross bar 109 of an inverted U-shaped wire spring, the legs 110 of which pass through the lower end portion of the member 105 and extend downwardly below the top 24 of the frame alongside the depending tongues 26. The legs are engaged by notched ears 111 on arms 112 that are secured to the rear end portions of the levers 28. With this construction the pawl 104 will not interfere with the rotation of the type wheel unless the keyboard 31 is depressed, and whenever the latter is depressed, the arms 112 will move forwardly and the ears 111 will act on the legs 110 of the wire spring to swing the member 105 and cause the pawl 104 to move in a direction away from the shaft 65, with the result that the pawl will interlock with a proper tooth of the ratchet 103 so as to temporarily hold the type wheel in position whether an upper or lower case character is being printed.

In operation the operator will turn either one or both of the knobs 82 to bring the proper character on one or the other of the wheels 83 into register with one of the pointers 85. In doing this, the type wheel 64, through the instrumentality of the gearing 80, 70, will be turned to bring the proper type character into position in front of the platen. Then if the operator presses downwardly on the corresponding key button of the keyboard, or on any other button of the latter, the rear ends of the levers 28 will move the platen forwardly to cause the paper on the platen to strike the portion of the inking ribbon 90 which is between the selected type character and the paper, with the result that the character is impressed on the paper. As soon as the key-

board is released, the springs 44 will function to return the keyboard and platen to normal position.

Whenever it is desired to space without printing, the spacing bar 60 is depressed, and this causes depression of the keyboard as well as forward movement of the platen. However, due to the abutment edges 61b, the spacing bar levers 61 cannot move downwardly sufficiently to cause the paper on the platen to be brought into contact with the ribbon.

When it is desired to print an upper case character, one or the other of the shift keys 102 is depressed. This causes the levers 99 to turn about the shaft 100 with the result that the abutment trough 98 acts against the lower end of the type wheel shaft 65 to raise the type wheel to the proper elevation to print an upper case character. If then the keyboard is depressed, the platen will be moved forwardly to cause printing of the desired character. Upon release of the shift key 102, spring 94 will function to assist in lowering the type wheel and to restore the shift keys to normal position.

Instead of manufacturing our typewriter in accordance with Figs. 1 to 11 inclusive, we can employ a simplified form of the invention such as illustrated in Figs. 12 to 14 inclusive. In this form a base 200 may be provided with an upstanding marginal U-shaped frame 201 having rearwardly extending arms 202 which support a horizontal shaft 203. The shaft supports the rear ends of rockable levers 204, the forward ends of which support a dummy keyboard 205 having key buttons 206 arranged to simulate a standard keyboard. The levers 204 support an inverted U-shaped member 207 forming a support for a rotatable platen 208. In this form of the invention, the platen is not axially movable.

Coil springs 209 connect the front end portions of the levers to the side walls of the frame to yieldingly hold the keyboard in raised position and in contact with the abutments 210 arranged on said side walls. Depression of the keyboard functions to move the platen forwardly.

Immediately forward of the platen, a shaft 211 is arranged and has its end portions journaled in the side walls of the frame. Knobs 212 are secured to the ends of the shaft for use in rotating the latter.

An index wheel 213 bearing characters corresponding with the characters of the keyboard, is fixed to one end portion of the shaft and cooperates with a stationary pointer 214 mounted on one of the side walls of the frame.

Immediately forward of the shaft 211, a second shaft 215 is arranged and has its ends fixed to the side walls of the frame. This shaft or rod functions as a guide for a sleeve 216 that is part of a carriage or casing 217. Within the latter there is a hub 218 having a square bore to slidably receive the square portion of the shaft 211. A type wheel 219 and a ratchet wheel 220 are fixed to the hub, and are arranged within the casing 217. The construction is such that the carriage and wheels may move lengthwise of the shafts 211 and 215, while the turning of the shaft 211 will cause rotation of said wheels.

A spring pawl 221 is secured to the carriage and arranged in the latter, and it engages the ratchet wheel to prevent accidental rotation of the shaft 211 and the parts which the shaft supports. A handle 222 is secured to the carriage and may be employed to shift the latter lengthwise of the shafts, and such movement is limited by abut-

ments 223 and 224 secured near the ends of the shaft 215.

A rack bar 225 of inverted U-shape has its legs 226 rockably connected to the sides of the frame as indicated at 227, and a spring 228 has one of its ends connected to one of said legs and its other end secured to one of the bearing arms 229 of the shaft 211, and this spring acts to urge the toothed portion of the rack toward said shaft. In order to cause forward movement of the rack bar each time the keyboard is depressed, the bar is provided with a fixedly connected forwardly projecting arm 230 which extends beneath the keyboard and is held in contact with the latter by means of the spring 228.

In order to permit the rack bar to be moved forwardly independently of the movement of the keyboard, the bar has a second forwardly and upwardly projecting arm 231 which forms a handle. A pawl 232 cooperates with the toothed rack to form an escapement mechanism. The pawl is pivotally mounted at 233 on the carriage 217, and a spring 234 cooperates with the pawl to urge the free end of the latter toward the teeth of the rack.

The carriage (Fig. 13) supports an inking roller 235 which contacts the type characters at the periphery of the type wheel.

In this form of the invention, the external frame has been omitted to facilitate a disclosure of the invention.

In operation, the paper is threaded about the platen in the usual manner, and the operator turns either one or both of the knobs 212 to cause the desired character on the index wheel 213 to register with the pointer 214. He then depresses the keyboard so as to cause the platen to move forwardly and drive the paper into contact with the type character which has been set up by the wheel 219. When the keyboard is depressed, it will cause the arm 230 to move the toothed portion of the rack bar 235 forwardly and out of engagement with the pawl 232. During such movement the pawl 232, under the influence of the spring 234, will swing a short distance in a counter-clockwise direction, whereby when the keyboard is released, and moves upwardly under the influence of the springs 209, the pawl will be in position to engage a succeeding tooth of the rack bar as the latter moves rearwardly. Obviously this will result in feeding the type wheel one step for each cycle of the keyboard.

For spacing purposes, of course, the front end portion of the handle 231 may be depressed so as to cause movement of the rack bar independently of the keyboard.

The other simplified form of the invention illustrated in Figs. 15 to 17 inclusive, is quite similar to the structure just described with the main exception that the frame of the machine rocks with the keyboard. In this embodiment, the base 300 carries a frame 301 having legs 302 which are pivotally connected at 303 to the base to allow the entire frame to rock about the horizontal axis of the pivots 303.

The false keyboard 304 is rigidly secured to the rockable frame and carries fixedly arranged key buttons 305 positioned to simulate the keyboard of a conventional typing machine.

Here also the rotatable platen 306 is fixed against axial movement. It is supported by a support 307 which has legs 308 fixedly secured to the rear end portion of the frame.

Between the platen and keyboard, a square shaft 309 is arranged and has its ends journaled (Fig. 17) in pedestals 310 fixedly supported by the base. One portion of the shaft is provided with a knob or handle 311 and an index wheel 312, both of which are fixed to the shaft. The index, of course, is provided with characters corresponding with the characters on the keyboard, and such characters cooperate with a stationary indicating finger 313 supported by a post 314 fixedly mounted on the base.

The opposite end of the shaft is provided with a ratchet wheel 315 (Fig. 17) which cooperates with a spring pawl 316 mounted on the base. The pawl prevents accidental rotation of the shaft.

A type wheel 317 is mounted on the square portion of the shaft so as to rotate with the latter and slide along the shaft, and this type wheel is also provided with a casing 318 which travels with the type wheel lengthwise of the shaft. Obviously, the type characters on the wheel correspond with the characters on the index wheel and the keyboard. The casing of the type wheel is of skeleton formation and is preferably provided with a shoe 319 that is guided across the machine by a track 320 fixed to the base. The type wheel is inked by an inking roller 321 supported by the skeleton casing, and the carriage may be provided with a handle 322 to allow it to be moved back and forth across the machine.

In this form of the invention the escapement mechanism is formed by a toothed rack bar 323 having legs 324 at its ends which are pivotally connected at 325 to the side edge portions of the base. The rack bar is urged in a rearward direction by means of a coil spring 326 having one of its ends connected to the bar and its other end anchored to the base as indicated at 327.

A pawl (Fig. 15) 328 is pivotally mounted at 329 upon the carriage or casing of the type wheel, and is urged in a counter-clockwise direction by means of a spring 330. The pawl, of course, cooperates with the teeth of the rack bar, and whenever the latter is moved forwardly out of contact with the pawl, the spring 330 will move the pawl into a position where it will engage a succeeding tooth of the rack bar when the latter returns rearwardly to normal position.

The rack bar has forwardly extending arms 331 which terminate at their forward ends in a spacing bar 332, positioned forwardly of the keyboard. The arms are connected by a cross bar 333 positioned immediately below the keyboard whereby when the latter is depressed, the spacing bar will also be depressed. For spacing purposes, the spacing bar can be depressed independently of the keyboard.

In using this form of the invention, the handle 311 is turned until the desired character on the index wheel 312 registers with the pointer 313 and this will bring the desired type character on the wheel 317 into printing position adjacent to the platen. Then when the keyboard is depressed the paper on the platen will be brought into contact with the selected type character. When pressure is released from the keyboard, the spring 228 will act to restore the keyboard and frame to normal position. During the printing operation, the escapement mechanism will function to feed the type wheel to the proper position for the next impression.

If the spacing bar 332 is depressed, the rack bar 75 can be moved out of contact with the pawl and

the type wheel can be shifted to any desired position along the shaft 309.

While we have disclosed what we now consider to be some preferred embodiments of the invention in such manner that they may be readily understood by those skilled in the art, we are aware that many modifications will be apparent to such persons without departing therefrom or from the scope of the claims, and since the disclosure has been given by way of examples, for clearness and understanding, no unnecessary limitations should be understood and the appended claims should be construed as broadly as the state of the art permits.

What we claim and desire to secure by Letters Patent is:

1. In a typewriter of the character having a forward depressible dummy keyboard and a rear rotatable platen, said keyboard being provided with key buttons adapted to be struck by the fingers of the operator, indicator cylinder means arranged between the platen and keyboard and rotatable about an axis parallel to the axis of the platen, a type member movable in synchronism with the indicator cylinder means and also arranged between the platen and the keyboard, stationary means cooperating with the indicator cylinder means to indicate the type character of the type member selected to be printed, means for simultaneously turning the indicator cylinder means and the type member, and means cooperating with the keyboard and platen for causing relative movement between the platen and type member, one toward the other, upon depression of the keyboard.

2. In a typewriter of the character having a movable type-carrying element, a cylindrical platen element, and a dummy keyboard operatively connected with one of said elements for moving the same toward the other upon depression of the keyboard, the improvement which comprises a casing, rotatable cylindrical indicating means arranged in the casing parallel to the platen element, stationary indicating means positioned in close proximity to said cylindrical means, one of said means including a series of indicating characters corresponding in appearance with the type characters on the type-carrying element, and the other indicating means being constructed and arranged to cooperate with said indicating characters to indicate the type character selected to be printed, and manually operated means for simultaneously turning said cylindrical indicating means to indicate a selected character and for shifting the type-carrying element to bring the selected type character into printing position.

3. In a typewriter of the character having a movable type-carrying element, a cylindrical platen element, and a dummy keyboard operatively connected with one of said elements for moving the same toward the other upon depression of the keyboard, the improvement which comprises rotatable cylindrical indicating means arranged parallel to the platen element and positioned between that element and the keyboard, said means including a plurality of co-axial wheels having a series of indicating characters corresponding in appearance with the type characters on the type-carrying element, the indicating characters on one of the wheels being arranged in staggered relation relatively to the indicating characters on the other one of said wheels, stationary indicating means positioned in close proximity to said cylindrical means to indi-

cate the type character selected to be printed, and manually operated means for turning said cylindrical indicating means to indicate a selected character and for shifting the type-carrying element to bring the selected type character into printing position.

4. In a typewriter of the character having a movable type-carrying element, a cylindrical platen element, and a dummy keyboard operatively connected with one of the elements for moving the same toward the other upon depression of the keyboard, the improvement which comprises a rotatable shaft arranged parallel to the axis of the platen element and positioned between that element and the keyboard, a second shaft on which the type-carrying element is mounted, gearing connecting the medial portion of the first-mentioned shaft to said second shaft, indicating wheels mounted on the first-mentioned shaft at opposite sides of said gearing, each of said wheels being provided with a series of indicating characters, the indicating characters on the wheels corresponding in appearance with the type characters on the type-carrying element, the indicating characters on one of the wheels being arranged in staggered relation relatively to the indicating characters on the other one of said wheels, stationary indicating means positioned in close proximity to said wheels for indicating the type character selected to be printed, and manually operated means for turning the first-mentioned shaft, whereby the wheels and type-carrying element are simultaneously turned.

5. In a typewriter of the character having an axially movable and rotatable type-carrying element, a cylindrical platen element, and a dummy keyboard operatively connected with one of said elements for moving the same toward the other upon depression of the keyboard, the improvement which comprises a bifurcated lever pivotally mounted for movement about a horizontal axis and having its inner end operatively connected to the type-carrying element for shifting the latter axially, said lever having forwardly projecting arms which extend beneath the keyboard and terminate in finger-engaging elements positioned at the forward portion of said keyboard.

6. In a typewriter of the character having a movable type-carrying element, a cylindrical platen element, and a dummy keyboard operatively connected with one of said elements for moving the same toward the other upon depression of the keyboard, the improvement which comprises a rotatable shaft arranged parallel to the axis of the platen element and positioned between that element and the keyboard, cylindrical indicating means mounted on and rotatable about the axis of said shaft, said means including a series of indicating characters corresponding in appearance with the type characters on the type-carrying element, stationary indicating means positioned in close proximity to said cylindrical means for indicating the type character selected to be printed, means operatively connecting the shaft to the type-carrying element to cause the type-carrying element to move in response to movements of the shaft, and manually operated means for turning said shaft.

7. In a typewriter of the character described, a depressible dummy keyboard having key buttons thereon adapted to be struck by the fingers of the operator, an inverted U-shaped rockable support movable about a horizontal axis extending through the lower end thereof, a platen unit

mounted upon said support, a rotatable type wheel arranged between the keyboard and platen unit and having type characters, yielding means cooperating with said rockable support and normally maintaining the platen in a position rearwardly of the type wheel, and lever means pivotally mounted at its medial portion for movement about a horizontal axis arranged forwardly of the first-mentioned horizontal axis, said keyboard being mounted upon the front end portions of the lever means, and the rear end portions of the lever means engaging the platen unit for moving the latter forwardly upon depression of the keyboard.

8. In a typewriter of the character described, a frame having oppositely disposed upstanding notched tongues and an aperture between the tongues, a sectional bearing having oppositely projecting pins detachably engaging the notches of the tongues, said bearing extending through said aperture, means detachably connected to the frame and engaging the bearing to prevent the latter from shifting in said aperture, a sleeve extending through the bearing, a bar carried by the sleeve and provided with notches, a type wheel having pins movable upwardly and downwardly in the notches of said bar, a shaft fixed to the wheel and extending downwardly through said sleeve, and means for rotating the sleeve.

9. A typewriter of the character described, comprising a depressible dummy keyboard provided with key characters, a platen unit arranged rearwardly of the keyboard, a type wheel positioned between the keyboard and platen unit and having type characters corresponding with the characters on the keyboard, means for rotating the type wheel to position a desired type character thereon in a position confronting the platen unit, means cooperating with the keyboard and platen unit for causing relative movement between said unit and the type wheel, one toward the other, upon depression of the keyboard, ratchet teeth united with the type wheel, a pivotally mounted pawl cooperating with said teeth, and a spring element operatively connected with the pawl and tensioned by the last-mentioned means during said relative movement.

10. A typewriter of the character described, comprising a depressible dummy keyboard provided with key characters, a platen unit arranged rearwardly of the keyboard, a type wheel positioned between the keyboard and platen unit and having type characters corresponding with the characters on the keyboard, first means for rotating the type wheel to position a desired type character thereon in a position confronting the platen unit, second means cooperating with the keyboard and platen unit for causing relative movement between said unit and the type wheel, one toward the other, upon depression of the keyboard, and locking means for the type wheel tensioned by the last-mentioned means during said relative movement, said locking means including a hingedly mounted pawl, an annular series of ratchet teeth carried by the wheel and engageable by the pawl, and a substantially inverted U-shaped spring engaging said pawl and having depending legs connected to and actuated by said second means.

11. In a typewriter of the character having a movable type-carrying element, a cylindrical platen element, and a dummy keyboard operatively connected with one of said elements for moving the same toward the other upon depression of the keyboard, the improvement which comprises a

5 casing, rotatable cylindrical indicating means arranged in the casing parallel to the platen element and positioned between the platen element and the dummy keyboard, said cylindrical indicating means including a series of indicating characters corresponding in appearance with the type characters of the type-carrying element, window means in the casing through which the cylindrical indicating means may be seen, stationary indicating means arranged on the casing adjacent to the window means and co-operating with the indicating characters on the cylindrical indicating means to indicate the type character selected to be printed, and manually operated means for turning said cylindrical indicating means to indicate a selected character and for shifting the type-carrying element to bring the selected type character into printing position.

15 12. In a typewriter of the character described, comprising a type wheel, a rockable support movable forwardly and rearwardly about a horizontal axis and having a platform movable toward and away from the type wheel, a platen having a carriage slideable along the platform and provided at its front edge portion with a toothed rack, a stationary support positioned below the platform, a lever pivotally mounted on the support for movement about a vertical axis, a platen advancing pawl, carried by one edge portion of the lever, a finger depending from the platform and engageable with the pawl for shifting the lever in a counter-clockwise direction, a locking pawl arranged at the opposite edge portion of the lever, both pawls being engageable with the teeth of the rack, and means for moving the movable platform and platen unit toward and away from the type wheel.

20 13. In a typewriter of the character described, a rotatable type wheel, a substantially horizontal table, a shaft for the type wheel extending through the table, a shift lever device having forwardly extending diverging arms pivotally mounted for movement about a horizontal axis, said arms being rigidly united at their rear ends and forming an abutment adapted to engage the lower end of the shaft for lifting the type wheel when the forward end portions of the levers are depressed, dummy keyboard means arranged forwardly of the type wheel and positioned over said arms, a platen unit arranged rearwardly of the type wheel, and means cooperating with the keyboard means and platen unit for causing relative movement between the platen and type wheel, one toward the other, upon depression of the keyboard means.

25 14. A typewriter of the character described, comprising a depressible dummy keyboard having key characters thereon, a rotatable platen spaced rearwardly from the keyboard, means for preventing the platen from moving axially, a rotatable shaft arranged between the platen and keyboard, an indicator wheel fixedly mounted on the shaft and having characters corresponding with the characters on the keyboard, a type wheel rotatable with the shaft and axially movable along the latter, a ratchet wheel movable along the shaft in synchronism with the type wheel and rotatable with the latter, a casing for the ratchet wheel and type wheel, said casing being movable lengthwise of the shaft in synchronism with the type wheel, a pawl in the casing cooperating with the ratchet wheel, means for guiding the casing, a rockable rack bar adapted to be moved in one direction by depression of the keyboard, and a spring-urged pawl carried by the casing

and cooperating with the teeth of the rack bar for feeding the type wheel along its shaft.

15. A typewriter of the character described, comprising a depressible dummy keyboard having key characters thereon, a rotatable platen spaced rearwardly from the keyboard, means for preventing the platen from moving axially, a rotatable shaft arranged between the platen and keyboard, an indicator wheel fixedly mounted on the shaft and having characters corresponding with the characters on the keyboard, a type wheel rotatable with the shaft and axially movable along the latter, a ratchet wheel movable along the shaft in synchronism with the type wheel and rotatable with the latter, a casing for the ratchet wheel and type wheel, said casing being movable lengthwise of the shaft in synchronism with the type wheel, a pawl in the casing cooperating with the ratchet wheel, means for guiding the casing, a rockable rack bar adapted to be moved in one direction by depression of the keyboard, a spring-urged pawl carried by the casing and cooperating with the teeth of the rack bar for feeding the type wheel along its shaft, and a handle connected to the rack bar for moving the latter in said one direction independently of the keyboard.

16. A typewriter of the character described, comprising a depressible dummy keyboard having key characters thereon, a rotatable platen spaced rearwardly from the keyboard, means for preventing the platen from moving axially, a rotatable shaft arranged between the platen and keyboard, an indicator wheel fixedly mounted on the shaft and having characters corresponding with the characters on the keyboard, a type wheel rotatable with the shaft and axially movable along the latter, a ratchet wheel fixed to the shaft near one end thereof, a stationary pawl cooperating with the ratchet wheel to control rotation of the shaft, a casing for the type wheel adapted to move lengthwise of the shaft in synchronism with the type wheel, means for guiding the casing, a rockable rack bar adapted to be moved forwardly by depression of the keyboard, and a spring-urged pawl carried by the casing and cooperating with the teeth of the rack bar for feeding the type wheel along its shaft.

17. A typewriter of the character described, comprising a depressible dummy keyboard having key characters thereon, a rotatable platen spaced rearwardly from the keyboard, means for preventing the platen from moving axially, a rotatable shaft arranged between the platen and keyboard, an indicator wheel fixedly mounted on the shaft and having characters corresponding with the characters on the keyboard, a type wheel rotatable with the shaft and axially movable along the latter, a ratchet wheel fixed to the shaft near one end thereof, a stationary pawl cooperating with the ratchet wheel to control rotation of the shaft, a casing for the type wheel adapted to move lengthwise of the shaft in synchronism with the

type wheel, means for guiding the casing, a rockable rack bar adapted to be moved forwardly by depression of the keyboard, a spring-urged pawl carried by the casing and cooperating with the teeth of the rack bar for feeding the type wheel along its shaft, and manually operated means including a spacing bar for moving the rack bar forwardly independently of the keyboard.

18. In a typewriter of the character having a forward depressible dummy keyboard and a rear rotatable platen, said keyboard being provided with key buttons adapted to be struck by the fingers of the operator and having characters thereon, a horizontal shaft arranged between the platen and keyboard and rotatable about an axis parallel to the axis of the platen, indicator cylinder means mounted on said shaft and having characters corresponding with the characters of the keyboard, a hand-operated member at one end of the shaft for actuating the latter, a type member movable in synchronism with the indicator cylinder means and also arranged between the platen and the keyboard, stationary means cooperating with the indicator cylinder means to indicate the type character of the type member selected to be printed, said type member having type characters corresponding with the characters of the keyboard, and means cooperating with the keyboard and platen for causing relative movement between the platen and type member, one toward the other, upon depression of the keyboard.

19. In a typewriter of the character described, a casing having an opening at the upper front portion thereof, a depressible dummy keyboard arranged to operate in said opening and having key characters thereon adapted to be struck by the fingers of the operator, a rotatable platen positioned above the rear portion of said casing, a manually operated rotatable shaft arranged parallel with the platen and positioned between the platen and keyboard, a handle operatively connected to said shaft and arranged at the exterior of one side of the casing, indicator cylinder means within the casing mounted on said shaft and having indicating characters thereon, a type wheel rotatable in synchronism with the indicator cylinder means and having type characters corresponding with the characters of the indicator cylinder means, said type wheel being arranged mainly within the casing, window means arranged in the casing rearwardly of the keyboard and through which the indicator cylinder means may be seen, and means in the casing cooperating with the keyboard and platen for causing relative movement between the platen and type wheel, one toward the other, upon depression of the keyboard.
